UNITED STATES PATENT OFFICE.

WILLIAM L. R. EMMET, OF SCHENECTADY, NEW YORK, ASSIGNOR TO
GENERAL ELECTRIC COMPANY, A CORPORATION OF NEW YORK.

MEANS FOR PREVENTING THE DISTORTION OF BUCKET-WHEELS.

No. 830,892.

Specification of Letters Patent.

Patented Sept. 11, 1906.

Application filed May 6, 1904. Serial No. 206,709.

To all whom it may concern:

Be it known that I, WILLIAM L. R. EMMET, a citizen of the United States, residing at Schenectady, county of Schenectady, State of New York, have invented certain new and useful Improvements in Means for Preventing the Distortion of Bucket-Wheels, of which the following is a specification.

It has been found in connection with elastic-fluid turbines, and particularly in those having wheels of large diameters, that when in operation a difference exists in the mean temperature on opposite sides of the wheel, and, further, that this difference varies under different conditions of operation. This temperature difference is sometimes noticeable in starting the turbine, as well as during its normal operation, and is usually detected by the sound occasioned by the rubbing of the relatively rotating parts. In other words, the temperature on one side of the wheel may be greater than on the other, and when this difference exceeds a certain amount it causes a prohibitive distortion or warping of the wheel parts. The difference in temperature is largely due to the fact that the temperature of the steam or other motive fluid leaking through the clearances between the nozzles or other discharging devices and the buckets and also around the shaft is above that discharged from the wheel, the said leakage being frequently in a superheated condition. The temperature difference is also due to radiation from the adjacent wall or diaphragm of the stage of higher pressure. Another reason for this difference is found in connection with those stages where by reason of their construction a difference in pressure exists on opposite sides of the wheel. My observation in connection with vertical-shaft machines having wheels occupying horizontal planes with the flow of motive fluid downward in an axial direction is that the excess temperature on the upper side may cause a downward deflection of the wheel, thereby causing the buckets on the exhaust side to rub unless the clearances are excessive. The same action may take place in horizontal machines; but in such event the distortion is in a horizontal or approximately horizontal direction instead of vertical or approximately vertical direction. The deflection is more noticeable in the last wheel of a turbine, wherein the active area of the

wheel is greater—as, for example, when the nozzles and intermediates cover the entire or substantially the entire circumference of the wheel; but it also takes place in other wheels located in stages or compartments of higher pressure.

Broadly, my invention contemplates the idea of preventing or reducing this distortion to a point where it can be disregarded by protecting the surface or surfaces of a turbine which are normally exposed to motive fluid by a suitable covering or mask applied at any suitable place or places, so that said surfaces will be less susceptible to temperature effects.

My invention also broadly contemplates the idea of compensating wholly or in part for any tendency which the turbine part or parts may have to warp or distort, due to unequal temperature effects.

The invention is applicable to turbines having one or a number of wheels in the same or separate compartments, and I do not limit myself to any particular wheel construction, either as to the body of the wheel or to the arrangement of the buckets. Neither do I limit myself to the character or arrangement of the devices which supply motive fluid to the wheel or to the controlling mechanism or to the arrangement of the buckets.

The particular wheel or wheels to be protected are provided with one or more coverings which cover the wheel wholly or in part, it being understood, of course, that the motive fluid must have proper access to the buckets. As an example of a covering I may employ one or more sheets of metal made in single pieces or subdivided, which are suitably attached to one or both sides of the wheel and extend from a point adjacent to the hub to a point at or near the periphery. Between the covering and the wheel or formed in the covering or in the wheel itself are one or more chambers which further serve to prevent distortion by causing the entire wheel to operate at a more nearly uniform temperature. To state the matter differently, the covering and chambers, considered together or separately, act to prevent sudden temperature changes from warping or distorting the wheel. The temperature of the wheel as a whole can be increased or decreased, as desired; but the changes should be brought about in such a

manner that no substantial difference exists at any given instant of time on those surfaces which are capable of causing distortion.

In order to compensate for any tendency to distortion which may exist under varying conditions of operation, I may connect one or all of the chambers with one or more sources of fluid-pressure which is capable of changing the temperature of the wheel parts to a certain extent. The arrangement of the chambers and supply-passages should be such that the effect of the fluid is readily felt over those surfaces which are capable of causing distortion. The chambers may be formed at the time the wheel is made or they may be formed in a built-up structure that is attached to the wheel.

In order to carry out the invention with existing constructions, a disk or covering, usually of metal, may be mounted on the inlet side of the wheel which covers the entire surface or a large portion of said surface. This disk can be attached in any suitable manner. Between the covering and the main body or web of the wheel is a chamber which may or may not contain a heat-resisting medium, or in certain cases a cooling medium may be introduced. On the exhaust side of the wheel is a suitable covering which protects that side of the wheel from the effects of the steam or other elastic fluid in the compartment in which the wheel is located. The covering may and preferably should cover all or a very large portion of its surface. Between the covering and the main body or web of the wheel is preferably a chamber of suitable size. This chamber is adapted to receive a heated medium—such, for example, as the motive fluid—for increasing the mean temperature of the exhaust side of the wheel. The fluid may enter the chamber in any suitable way. I have shown two such ways. In one case the fluid enters through one or more openings or passages formed in the web of the wheel, and in the other case through one or more passages formed in the hub of the wheel. These latter passages are arranged to receive the fluid which leaks from one stage to another around the packings. In this manner the leakage fluid is rendered more effective than heretofore and any tendency to warping or distortion compensated for. Arranged at one or more suitable points in the covering, and preferably out of line with the inlet-passage, are passages or openings through which the fluid escapes after having given up its heat or a certain per cent. thereof to the surfaces of the wheel. The fluid thus escaping from one wheel discharges into a compartment in which it is collected and renozzled in all stages except the last, where it passes to the condenser or other exhaust.

It will be seen that the motive fluid has two paths, the normal or main path through the nozzles, wheel, buckets, and intermediate

buckets, where the latter are used, and an auxiliary path conveying a small portion of the fluid for heating purposes alone. The main and auxiliary paths are arranged in multiple, the former being of relatively low resistance and the latter of relatively high resistance. 70

It is desirable to cover both the admission and exhaust sides of the wheel, but the covering on the admission side can be omitted under certain conditions, and I aim to embrace this arrangement in the claims. 75

In the accompanying drawings, which illustrate one embodiment of my invention, Figure 1 is a partial vertical section of a jet-turbine of the multistage type having two rows of wheel-buckets per stage. Fig. 2 is a transverse section of the same. Fig. 3 is a detail sectional view showing the arrangement of the inlet and outlet ports or passages 80 for conveying motive fluid into and out of the chamber on the exhaust side of the wheel, and Fig. 4 is a detail perspective view of one of the channel-irons employed to support the covering. 85

1 represents the main shaft, upon which are mounted one or more bucket-carrying wheels 2. Each of these wheels is provided with one or more rows of buckets 3. In the present instance each wheel is provided with two rows of buckets. Four wheels are shown in the present construction, which are inclosed in a casing 4, made up of suitable sections. The wheels are separated one from the other by diaphragms 5, which divide the casing into compartments, a single wheel being located in each compartment. Between the diaphragms and the shaft or the hub of the wheel is a packing 6 for reducing the leakage between the wheel-compartment 90 and the next. Steam or other elastic fluid is supplied to the wheel-buckets by a valve-chest 7, which is connected to the source of supply. Mounted in the valve-chest are a number of valves 8, each of which is actuated by a piston 9, that is or may be under the control of a relay-valve, the latter being controlled by a speed-responsive device. Each valve controls the passage of fluid to one or more nozzles or nozzle-sections 9', which in turn discharge the fluid at the proper angle against the buckets. Where two or more rows of buckets are provided for each wheel, intermediate buckets 10 are provided between two rows of wheel-buckets. The arrangement of the nozzles and buckets is the same throughout the machine, except that the active portion of the wheel gradually enlarges from the inlet to the exhaust. 110

The wheel-casing is mounted on a base 11, which contains a chamber 12, that is connected to a condenser or to the atmosphere, as is desired. Mounted on the upper surface of each wheel to be protected are concentric rings or supports 13 and 14, which support 120 130

the protecting-covering 15, the latter being of disk-like formation and made up of one or more pieces. In the present construction this covering is made up of two sections of sheet metal riveted together, as shown in Fig. 2. The covering is supported at intermediate points by channel-irons 16, shown in dotted lines in Fig. 2 and in perspective in Fig. 4. On the under side of the wheel are attached concentric supporting-rings 17 and 18, to which the covering 19 is attached. This covering is supported at intermediate points by channel-irons 20 of the same character, as shown in Fig. 4. Between each of the coverings and the web of the wheel is a chamber 21, the chamber on the upper side of the wheel acting simply as a dead-air space or chamber, while the chamber on the under side is connected to the steam-space above the wheel by one or more openings, passages, or conduits 22. In the present illustration there are a number of circular openings near the periphery of the wheel and other openings near the hub of the wheel. In addition to these are passages 23, formed in the hub of the wheel, which communicate with grooves formed in the packings 6, so that any leakage through the packing will be diverted into the chamber on the under side of the wheel.

In order to permit the fluid to pass from the chamber either on the under or upper side of the wheel after giving up a certain amount of its heat to the wheel parts or cooling it, as the case may be, one or more openings or passages 24, Fig. 3, are provided, the said passages being offset from the inlet-passages to prevent the steam or other fluid from passing directly from the inlet to the outlet without giving up heat to the wheel.

In the drawings three separate sets or series of inlet ports or passages are provided for supplying steam to the chamber on the under side of the wheel, but in some cases certain of these passages can be omitted.

From actual tests of my invention I have found that objectionable wheel distortions can be obviated and that the compensation may even be in excess of that required and actually cause the buckets to move up instead of down.

In accordance with the provisions of the patent statutes I have described the principle of operation of my invention, together with the apparatus which I now believe to represent the best embodiment thereof; but I desire to have it understood that the apparatus shown is only illustrative and that the invention can be carried out by other means.

What I claim as new, and desire to secure by Letters Patent of the United States, is—

1. A turbine comprising a casing and relatively movable parts, in combination with a protecting-covering attached to and moving with a part for preventing objectionable distortion thereof.

2. A turbine comprising a casing and a bucket-wheel, in combination with a protecting-covering applied to the web or body of the wheel.

3. A turbine comprising a casing and a bucket-wheel, in combination with a protecting-covering for the web or body of the wheel and means for attaching the covering to the wheel.

4. A turbine comprising a casing and a bucket-wheel, in combination with a protecting-covering for both sides of the web or body of the wheel.

5. A turbine comprising a casing and a bucket-wheel, in combination with a protecting-covering for one side of the wheel, and a chamber situated between the covering and the wheel.

6. A turbine comprising a casing and a bucket-wheel, in combination with protecting-coverings for both sides of the wheel, and a chamber situated between each covering and the wheel.

7. In a turbine, the combination of a casing, a chambered wheel, and a conduit for admitting fluid to the chamber.

8. A turbine comprising a casing and a bucket-wheel, in combination with a protective covering carried by the wheel for preventing it from distorting, said covering being independent of the bucket-supporting portion.

9. A turbine comprising a casing and a bucket-wheel, in combination with a disk-like covering for equalizing the mean temperature on the admission and exhaust sides of the wheel.

10. A turbine comprising a casing and a bucket-wheel, in combination with a means admitting motive fluid at a temperature above that in the wheel-compartment for increasing the temperature of the exhaust side of the wheel.

11. A turbine comprising a casing and a bucket-wheel, in combination with chambers moving with the wheel and arranged to receive a fluid for equalizing the mean temperature on opposite sides of the wheel.

12. A turbine comprising a casing and a bucket-wheel, in combination with a protecting-covering for one side of the wheel, containing a chamber, and an opening or passage for conveying a heat-imparting fluid to the chamber.

13. In a turbine, the combination of a casing, a chambered wheel, driving-buckets carried by the wheel, and an opening or passage for conveying motive fluid from one side of the wheel into the chamber.

14. In a turbine, the combination of a casing, a chambered wheel, driving-buckets carried by the wheel, and an inlet and an outlet opening or passage for the chamber.

15. In a turbine, the combination of a casing, a chambered wheel, buckets on the

4
wheel, nozzles discharging fluid against the buckets, an inlet opening or passage located near the periphery of the wheel, and an outlet opening or passage located at a point remote therefrom for preventing wheel distortion.

16. In a turbine, the combination of a casing, a chambered wheel, inlet-openings located near the center and near the periphery of the wheel, and outlet-openings located between the inlet-openings.

17. In a turbine, the combination of a chambered bucket-wheel, a casing therefor, a wall situated within and dividing the casing into compartments, a packing for reducing the leakage around the wheel-shaft, and a passage leading from the packing to the chamber in the wheel.

18. A turbine comprising a casing and a bucket-wheel, in combination with means located on opposite sides of the wheel for equalizing the temperatures.

19. In a steam-turbine, the combination of a chambered bucket-wheel, a casing therefor, a device for protecting the inlet side of

the wheel from hot steam, and means for directing hot steam against the exhaust side of the wheel.

20. In a turbine, the combination of a wheel, a casing therefor, buckets on the wheel between which the major portion of the motive fluid passes to produce rotation, and an auxiliary path through which the motive fluid passes to equalize the mean temperatures on opposite sides of the wheel. 35

21. A turbine comprising a casing and relatively movable parts, buckets carried by one of the parts, and devices for discharging fluid against the buckets, in combination with a means rotating with one of the parts for preventing the temperature of the part from suddenly changing and producing objectionable distortion. 40

In witness whereof I have hereunto set my hand this 5th day of May, 1904.

WILLIAM L. R. EMMET.
